UNITED STATES PATENT OFFICE.

CHARLES A. ANDERSON, OF CHICAGO, ILLINOIS.

PUMP.

Application filed October 16, 1919. Serial No. 331,075.

To all whom it may concern:

Be it known that I, CHARLES A. ANDERSON, a citizen of the United States, residing in the city of Chicago, county of Cook, and State of Illinois, have invented certain new and useful Improvements in Pumps, of which the following is a specification.

This invention relates to improvements in pumps and refers more particularly to an air pump which is adapted for use on motor cars and the like, although in its broader aspects, the invention is adapted for a wide variety of uses.

Among the salient objects of the invention are to provide a construction which insures of the pump being properly cooled by having the cylinder rotate in open air, thus keeping it air-cooled; to provide a construction of the character referred to in which the piston is operated from a stationary cam and the piston and cylinder rotate together; to provide a construction which has no valves liable to get out of order and subject to the objections to which ordinary valves are subject; to provide a construction in which the pressure may be readily varied by varying the tension between the cylinder and the driving member; to provide a construction which can be so arranged that it will not pump beyond a predetermined pressure; to provide a construction which is adapted for pumping up tires on a motor car such as a Ford, by merely attaching it to the fan shaft and operating it from the fan belt; to provide a construction which can be readily applied or removed from any given driving member and in general to provide an improved construction of the character referred to.

In the drawings:

Fig. 1 is a fragmentary side elevation of the device with parts shown in dotted lines to bring out the details of construction.

Fig. 2 is a top plan view with parts shown in dotted lines.

Fig. 3 is an elevation of the side opposite Fig. 1 but showing the pump in inoperative position.

Fig. 4 is a sectional detail taken through the rotating cylinder.

Fig. 5 is a fragmentary sectional detail view showing the air port arrangement.

Referring to the drawings, 1 designates a suitable support, which, in this instance, is the fan bracket of a motor car, upon which

bracket is mounted the motor fan plates 2, driving pulley 3 and pulley belt 4. A supporting arm 5 is secured to the bracket 1 by means of clamp 6 rigidly affixed to the bracket by screw 7. In the outer end of the arm 5 is journaled a pin 8 which is fixedly attached to frame member 10 of the pump 9. The frame member 10 is adapted to rock the pump in or out of operative position on the journal shaft or pin 8, by means of handle 11. The pump 9 is held in operative position by means of a tension spring 12 secured at 13 to the rear end of arm 5 and secured at 14 to a rod 15 which extends through the frame member 10. The downward movement of the frame, when being thrown into inoperative position is limited by means of a stop 16 which takes up against the tail piece 17 of the frame member 10.

Describing now the pump construction proper, the pump cylinder 18 is provided with journal shaft 19 which is rotatably mounted in a journal boss 20, which forms part of the frame member 10. The periphery 21 of this cylinder is adapted to frictionally engage with the pulley belt 4, and is provided with piston 22, reciprocating in cylinder 18. The piston is provided with a piston rod or bracket 23 pivoted at 24 to a rock arm 25, which rock arm 25 is pivotally connected by means of pintle 26 to brackets 27 mounted on the cylinder casing. The rocker arm 25 is right angle in form, the end 25a of which extends through the cylinder casing, through hole 28 where its end is movably engaged in an aperture 29 in the eccentric strap 30. This eccentric strap is operated by eccentric 31 which is fixed to the frame member 10.

The arrangement is such that when the pump frame is in position shown in Fig. 1, the cylinder will frictionally engage the belt 4 and be held against the same by means of spring 12. If the pressure on the piston goes beyond a predetermined point, the belt 100 will not operate the piston, thus preventing the pumping of air beyond a predetermined pressure. This predetermined point is fixed by the amount of tension put on the spring 12.

Describing now the port arrangement for the pump, in the boss 20 is an air port 32 which is adapted to register with the air duct or port 33 formed in the shaft of the cylinder. This port 33, of course, rotates 110

with the cylinder and is adapted to communicate also with an outlet port 34 formed in the boss 20. The port 34 is connected to an air hose or other connection 35. The arrangement is such that as the piston moves outwardly, the air is drawn in, whereupon the duct 33 has rotated out of communication with the inlet port 32. As the piston reaches the lower part of its stroke, the port 33 communicates with the port 34 and the air is pumped into the hose 35. One feature of the invention lies in the fact that a relatively powerful air pump can be obtained by a very small device as the cylinder can be only a few inches in cross section. A screw 36 joins the two portions of the split bearing 20 and furnishes a means of taking up the wear in this bearing. This is an important feature in that any looseness in this bearing will cause a leakage of air pressure, the pressure through the outlet 35 being dependent upon a close fitting bearing 20.

The operation of the device is as follows: The eccentric being fixedly attached to the frame member 10 remains stationary while the eccentric strap 30, rotating with the cylinder, operates the rocker arm 25, as the eccentric strap is engaged with the lower end of the rocker arm 25^a. The rocker arm, pivoted at 26 and connected with the piston bracket at 24, transmits a reciprocating motion to the piston.

It is apparent to those skilled in the art that the details of construction can be varied without in any way departing from the spirit or scope of the invention.

I claim as my invention:

1. In a pump, the combination with a driving member, of a rotatable cylinder frictionally driven from said driving member and having a reciprocating piston therein, a bell crank lever pivoted on said rotating cylinder operated through a stationary eccentric and transmitting the reciprocating movement to the piston, and inlet and outlet ports controlled by the rotation of the cylinder.

2. In a pump, the combination with a driving member, of a pump frame having a cylinder and piston rotatively mounted thereon, a spring for holding the surface of the cylinder in frictional engagement with the driving member to rotate the cylinder on its axis, a bell crank lever pivoted on said rotating cylinder and operated through an eccentric, to reciprocate the piston in the cylinder.

3. In a pump the combination with a driving member, of a cylinder, a piston and hollow shaft rotating together on the axis of the shaft, the hollow chamber of the shaft having communication with the piston chamber of the cylinder, a bearing for carrying said shaft having inlet and outlet ports therein, adapted to register with the

port in the hollow shaft upon the rotation of the shaft, a stationary eccentric having connections with the piston and functioning to reciprocate the piston with the rotation of the cylinder.

4. In a pump, the combination with a driving member of a rotating cylinder frictionally driven from said driving member, a hollow shaft extension to the axis of the cylinder communicating with the piston chamber and integral with the cylinder, a bearing carrying said shaft extension having inlet and outlet ports therein adapted to register with a port in the hollow shaft upon the rotation of the shaft, a piston rotat- 75 ing with the cylinder and means for reciprocating said piston. 80

5. In a pump, the combination with a rotating cylinder having a piston therein, of a hollow shaft extension to the axis of the cylinder communicating with the piston chamber, a stationary eccentric having operable connections to the piston, and functioning with the rotation of the cylinder to reciprocate the piston, a bearing with inlet 90 and outlet ports carrying said shaft extension, a port leading into the hollow shaft and adapted upon the rotation of the shaft to register alternately with the inlet and outlet ports in the bearings. 95

6. In a pump, the combination with a rotatable cylinder and piston, of a hollow shaft extending from the axis of the cylinder and integral therewith, the longitudinal duct in said hollow shaft communicating with the piston chamber of the cylinder, a bearing having inlet and outlet ports therein carrying said shaft, a port in the hollow shaft connecting with said duct and adapted to register with the ports in the bearing 100 upon rotation of the shaft, a stationary eccentric and lever arm functioning to reciprocate the piston with the cylinder. 105

7. In a tire pump the combination with a fan belt of an automobile, of a cylinder having a reciprocating piston therein, a hollow shaft extension from the axis of the cylinder, the longitudinal duct in the hollow shaft communicating with the piston chamber of the cylinder, a bearing carrying said shaft extension with inlet and outlet ports adapted to register with a port in the hollow shaft, a bell crank lever pivoted on said cylinder and operated thru a stationary eccentric for reciprocating the piston, means for rotating the cylinder piston and shaft extension by frictional engagement of the cylinder surface with the fan belt. 115

8. In a tire pump, the combination with the fan belt of an automobile of a cylinder having a reciprocating piston therein, a hollow shaft extension from the cylinder axis, comprising both inlet and outlet ducts communicating with the piston chamber of the cylinder, a bearing supporting the shaft ex- 120 125 130 135 140 145 150

- tension having inlet and outlet ports alternately communicating with the longitudinal duct to the piston chamber, means for reciprocating the piston, means for rotating the cylinder, piston and shaft extension on their common axes by frictionally engaging the cylinder surface and fan belt.
9. In a tire pump the combination with the fan belt of an automobile, of a cylinder adapted to be axially rotated with a reciprocating piston therein, means for reciprocating said piston, inlet and outlet ducts communicating with the piston chamber and means for frictionally driving said cylinder from the fan belt.
10. In a pump and in combination, a bearing, a hollow shaft having an air passage therein, a friction wheel mounted on said shaft, a piston reciprocating along the line of the shaft, means for operating said piston on the revolution of the shaft, and inlet and outlet ports in said bearing.
11. In a pump and in combination, a bearing, a hollow shaft having an air passage therein, a friction wheel mounted on said shaft, a piston reciprocating along the line of the shaft, a lever adapted to reciprocate said piston, a cam for oscillating said lever as said wheel rotates, and inlet and outlet ports in the shaft whereby the reciprocation of the piston serves to perform a pumping action.
12. In a pump, a bearing, a hollow shaft, an enlarged friction wheel on one end of said shaft, a cylinder in said friction wheel concentric with said hollow shaft, a piston in said cylinder, and valve mechanism associated with said hollow shaft.
13. In a pump, a bearing, a hollow shaft, a cylinder mounted on said shaft and having its axis parallel to the axis of the shaft, a piston reciprocating in the cylinder, and a stationary means having connection to the piston operating the piston with the rotation of the shaft.
14. In a pump, a shaft having a bore therein, a rotary element mounted on said shaft, a cylinder in said element, a piston in said cylinder, a stationary means for reciprocating said piston as the element rotates.
15. In apparatus of the class described, and in combination, a bracket adapted to be secured upon an automobile adjacent a rotary part, an arm pivoted in said bracket, a rotary pump element on said arm, said arm being movable to move said pump element into and out of contact with the rotary part, and yielding means to hold said element in said contact.
16. In apparatus of the class described and in combination with a driving member, an adjustable bearing, a rotary pumping element mounted in said bearing, and means whereby said bearing may be moved to bring said rotary pumping element into and out of operative connection with the driving member.

CHARLES A. ANDERSON.
